UNITED STATES PATENT OFFICE

SAMUEL W. SIDER, OF LOGANSPORT, INDIANA

DEVICE FOR HULLING OATS AND LIKE GRAINS

Application filed January 16, 1930. Serial No. 421,236.

This invention relates to devices for hulling oats and like grains, and has for its object to provide an arrangement of this character which combines a pneumatic suction effect with a vibratory screen arrangement and in operation effectively hulls and separates the grain from the groats, chaff, dust and other particles with which it is ordinarily contaminated.

A further object of the invention is the provision of a device of the above character in which a portion of the heavier material subsequent to its first run through the hulling device is returned to the rotary huller for retreatment to ensure against the unintentional loss of grain.

A still further object of the invention consists in an arrangement of this character wherein the material is caused to traverse the hulling machine and to be subjected to the effects of air draft in such manner as to ensure maximum output of grain with a minimum expenditure of power and time.

With the foregoing and other objects in view the invention consists in the novel construction, arrangement and combination of parts as will be hereinafter more fully described in connection with the accompanying drawing, in which

Fig. 1 is a top plan view of the complete machine;

Fig. 2 is a vertical longitudinal section therethrough;

Fig. 3 is a transverse section on the line 3-3 of Fig. 1; and

Fig. 4 is a detail sectional view.

Referring to the drawing in detail, the numeral 5 indicates an upright supporting frame the vertical members of which are connected medially by horizontal beams 6 in which the vibratory frame designated at 7 is mounted to oscillate about pivot points 8.

The upper part of the supporting frame 5 supports a receiving hopper 9 into which the material to be hulled and separated is deposited and which communicates at its lower end with one end of the casing 10 for the rotary hulling cylinder 11 which is suitably mounted to rotate within the casing 10. Both the cylinder and casing are provided with

breaker plates, corrugations and like devices for ensuring the loosening and removal of the hulls and the loosening of such foreign material as may accompany the grain, and the extremity of the casing 10 opposite that communicating with the hopper 9 is provided with an outlet 12 which is slightly inclined upwardly and in the direction of the frame 5 opposite the end on which the hopper 9 is supported.

Directly below the outlet 12 there is arranged a hollow platform or receiving table 13 adapted to receive the grain, hulls and other material ejected from the opening 12, and the platform 13 is suitably inclined so as to cause the material deposited thereon to move downwardly by gravity until it falls over the lowermost edge.

As stated, the inclined platform 13 is of hollow form, and the interior 14 thereof is open from end to end and communicates at one extremity with the inlet of a fan casing 15 in which is located a centrifugal fan 16. The outlet of the fan 15 is indicated at 17 and is in communication with a suitable dust receptacle to which the relatively light dust and hull particles separated from the grain are carried. A controlling valve 18 for the conduit 14 is provided for controlling the uptake of air therethrough, and as will be understood, the lower open extremity of the conduit 14 is disposed to entrain the hulls and lighter particles descending with the grain moving downwardly along the inclined platform 13.

As shown in Fig. 2, the platform 13 is so disposed as to cause the deposit of the material in the frame 7 at a point substantially directly beneath the cylinder casing 10. Owing to this arrangement, the dimensions of the device may be reduced without sacrifice of efficiency.

A series of three correspondingly inclined scalping separators 20 are mounted in the frame 7 and the lower extremities thereof extend into openings provided in a fall pipe 21 in communication with the fan casing 15. Below each of the inclined separators 20 which are adapted to carry off the rough material there is arranged an oppositely in-

clined plate 21 adapted to carry the material from one separator 20 to the next adjacent one thereunder, while a steel separating plate 22 provided with a plurality of apertures of predetermined size and arrangement is located beneath the lowermost separator 20. A flat steel plate 23 is supported a predetermined distance above the separating plate 22 and is adapted to retain the material in a horizontal position on the plate 22 and prevent the larger material from assuming a vertical position, making it impossible for it to pass through the perforations in the plate 22, but allowing the smaller material to pass through the perforations in said plate and on to the final receiving plate 24 which is inclined to cause the material to be deflected to the desired point for delivery.

An endless conveyor or elevator 25 is located in a tube 26 communicating with the lower end of the fall pipe 21 and extending to the upper end of the receiving hopper 9 whereby the heavier particles of material descending from the fan casing 15 are returned to the casing 10 for retreatment by the huller and separator.

The vibratory frame 7 is connected through a link 28 with the crank pin of a crank shaft 29 suitably mounted in bearings 30 on the upper right frame 5, whereby vibratory movement is imparted to the frame 7, and the shaft 29 is connected by a power transmitting device 31 with the pulley 32 on the supporting shaft of the cylinder 11, the movement of the latter being transmitted to the rotor 16 through a second power transmitting device 33. A belt or like power transmitting device 34 connects the shaft 29 with the upper shaft of the conveyor or elevator 25, whereby operation of the latter is effected.

As shown in Fig. 2, the fall pipe 21^a is provided with a damper or valve 35 by which the passage of air therethrough may be controlled while the chamber in the frame 5 directly above the inclined platform 13 is in communication with a suction pipe 36 into which the chaff, dust and other like foreign material emerging from the outlet 12 is entrained.

50 What I claim is:

1. A grain huller comprising a vibratory frame embodying a plurality of superposed separator members, a hulling cylinder disposed above the frame and provided with an upwardly inclined outlet, a stationary inclined platform also disposed above the vibratory frame with its extremity underlying the outlet of the hulling cylinder, and a suction fan disposed at the end of said platform remote from the hulling cylinder, the platform being hollow and defining an internal suction conduit in communication with the intake of the fan.

65 2. A grain huller comprising a vibratory frame embodying a plurality of superposed

separator members, a hulling cylinder disposed above said frame at one end and having an upwardly inclined outlet, a stationary platform also disposed above said frame with one end underlying said outlet, said platform being hollow to define an internal suction conduit, a fall pipe disposed at one end of said frame and in communication with the separators thereof, and a suction fan having its intake in communication with said fall pipe and with said suction conduit.

3. A grain huller comprising a vibratory frame embodying a plurality of superposed separator members, a hulling cylinder disposed above said frame at one end and having an upwardly inclined outlet, a stationary platform also disposed above said frame with one end underlying said outlet, said platform being hollow to define an internal suction conduit, a fall pipe disposed at one end of said frame and in communication with the separators thereof, and a suction fan having its intake in communication with said fall pipe and with said suction conduit, said fall pipe and said suction conduit being provided with manually actuatable valves for the selective control of the passage of air through each.

In testimony whereof I affix my signature.

SAMUEL W. SIDER.
